Primary Examiner — Daniel J Domino(74) *Attorney, Agent, or Firm* — Goodwin Procter LLP(57) **CLAIM**

The ornamental design for a computer display with graphical user interface, as shown and described.

DESCRIPTION

FIG. 1 is a front view of a computer display with graphical user interface;

FIG. 2 is a front view of a computer display with graphical user interface depicting an alternate embodiment of the invention;

FIG. 3 is a partial, magnified front view of the graphical user interface of FIG. 1; and,

FIG. 4 is a partial, magnified front view of the graphical user interface of FIG. 2.

The broken line showing of a computer display and elements of a user interface is included for the purpose of illustrating portions of the article and forms no part of the claimed design.

1 Claim, 3 Drawing Sheets(56)
